HEDDLE FRAME

George F. Bahan, Charlotte, N. C.

Application January 21, 1935, Serial No. 2,825

4 Claims. (Cl. 139—91)

This invention seeks to provide a heddle frame which will be strong and durable and in which the parts will be rigidly held together but may be separated when it is necessary, for any reason, to disassemble the frame or other parts. It is also an object of the invention to provide a structure in which the heddle bars and the supports therefor will all be within the inner lines of the frame and will, therefore, not be liable to damage from chance blows. It is also an object of the invention to provide novel means for retaining the heddle bars in place without requiring any weakening of the ends of the heddle frame. Other objects will appear incidentally in the course of the following description and the invention resides in certain novel features which will be particularly pointed out in the appended claims.

In the drawing:

Figure 1 is an elevation of one end of a heddle frame embodying the present invention.

Figure 2 is an enlarged view of one corner of the heddle frame on an enlarged scale, with parts in section.

Figures 3, 4 and 5 are enlarged views, partly in elevation and partly in section of the heddle bar lock, showing different positions of the same.

Figure 6 is a plan view of the lower rail, with parts in section, on the line 6—6 of Figure 2.

The heddle frame comprises wooden top and bottom rails 1 and end bars 2 with means for connecting the end bars and the rails so that the right angular formation will be maintained and a strong frame will be produced, but the parts may be readily separated when necessary. The rails are formed in their upper and lower edges with recesses to receive metallic plates 3 and 4 which extend somewhat beyond the ends of the rails and are formed at their ends with eyes to receive a cap screw or bolt 5. The ends of the rails are also dished or made concave so as to fit closely to a spacing sleeve 6 which is interposed between the ends of the plates 3 and 4 and has its bore aligned with the eyes in said plates. The ends of the sleeve 6 abut squarely against the opposed faces of the plates 3 and 4 so that a right angular fastening is provided and the ends of the end bars 2 likewise abut the inner or opposed surfaces of the plates 3 secured to the lower edge of the top rail and the top edge of the lower rail, as shown. The end bars 2 are tubular and their bores are threaded at their extremities, as indicated at 7, to receive the threaded ends of the cap screws or bolts 5. The cap bolts are inserted through the plates 3 and 4 and the sleeves 6 to engage the threaded ends 7 of the end rods and turned home so that their heads 8 will abut the plates 4, as clearly shown in Figure 2. When these cap bolts or screws are turned fully home, the top and bottom rails will be very firmly secured to the end bars so that the rectangular form of the heddle frame will be maintained, but the parts may be obviously readily separated when disassembling is necessary for any reason. The plates 3 and 4 are firmly secured to the rails by wood screws 9 inserted through the plates into the rails, as will be understood and as shown in Figure 2, and the recesses formed in the rails are of such dimensions that the plates will fit snugly therein with their surfaces flush with the edges of the rails.

In the top edge of the bottom rail and the bottom edge of the top rail, a notch 10 is formed in the base of the recess therein at the end of the rail, as clearly shown in Figure 2, and the plate 3 is provided with a rectangular slot near its end to receive the rectangular shank 11 of a stud 12 which extends inwardly with respect to the plate, the shank being upset against the plate and the upset extremity being accommodated in the notch 10, as will be understood upon reference to Figure 2. The stud 12 is located adjacent the end bar of the frame but out of contact therewith and near its upper end is formed with a recess 13 which provides a seat for the end of the heddle bar 14. Below the recess 13, a shallower recess 15 is provided in the side of the stud for a purpose which will presently appear, and it may be noted that the stud is non-circular in cross section so that a latching member mounted thereon will be prevented from rotating and will always be in proper operative position relative to the stud. Movable mounted upon the stud is a latching sleeve or heddle bar lock 16 which, of course, has a cross sectional contour corresponding to the cross section of the stud so that relative rotation of the lock will be prevented. The lock is of tubular formation and is provided in one side with a recess 17 adapted to accommodate the heddle bar, and, from the upper end of said recess, a notch or slot 18 extends upwardly so that the sleeve may be engaged over the heddle bar when it is desired to lock the same in place. The locking tube or sleeve 16 is formed with longitudinal slits 19 extending upwardly from the upper end of the recess 17 thereby producing a tongue 20 which is somewhat resilient and which, in the lowered position of the lock, will bear against the side of the heddle bar, as indicated by the dotted lines in Figure 3, while in the upper position of the lock, it may be bent outwardly from the lock, as indicated in Figure 4, thereby permitting separation of the sleeve from the heddle bar. In the lower wall of the recess 11, short slits 21 are formed thereby defining a resilient lip 22 which engages and plays in the recess 15 in the stud 12. When the locking sleeve 16 is drawn upwardly to release the heddle bar, the lip 22 abuts the upper shoulder or end wall of the recess 15, as shown in Figure 4, and

thereby arrests the upward movement of the sleeve so that while the heddle bar may be released the locking sleeve will be retained in position upon the stud. The locking sleeve is also provided at its upper end with corrugations 23 to facilitate gripping of the sleeve by the fingers of an operator when, for any reason, the sleeve is to be shifted.

From the foregoing description, taken in connection with the accompanying drawing, it will be seen that I have provided a very strong construction whereby the rectangular form of the heddle frame will be maintained through the life of the frame and whereby the heddle bar will be firmly supported and retained in place without requiring any projections upon or openings in the end bars of the frame. In assembling the parts, the locking sleeve 16 is raised to the position shown in Figure 4 and the end of the heddle bar 10 may then be moved laterally to enter the recess 13 of the stud and rest upon the lower shoulder or end wall of said recess, it being obvious that in this position of the locking sleeve the opening or recess 17 therein will be in position to admit 15 the heddle bar. After the bar is in place, the sleeve is moved downwardly and the slot or notch 18 will be thereby caused to engage over the heddle bar, as shown in Figure 3, and lock the heddle bar in place. The resilient tongue 20 will 20 bear against the side of the heddle bar so that any lost motion between the heddle bar and the lock will be taken up and overcome. When the lock is moved upward to release the heddle bar, the spring tongue 20 will be caused to move outwardly by riding against the upper end portion 25 of the stud.

It will be readily noted that there are no latches, springs or wires outside the inner boundary lines of my improved heddle frame and the 40 rails and end members of the frame are very securely clamped together so that the frames will withstand rough usage without becoming distorted. In the operation of a heddle frame in the loom, it becomes necessary, at times, to 45 make repairs or to replace a rail or other defective parts while the frame is in the loom and my construction facilitates such an operation. Finger pressure upon the locking tube will release the heddle bar and then, by merely removing 50 the cap screws at each end of the bottom rail, the rail will be released and the remaining portion of the heddle frame will be free so that it can be removed from its position in the loom leaving the heddles and heddle bars in proper relation to the warp within the loom. Should it be 55 necessary to add heddles to the frame or remove some of the heddles, the releasing of the heddle bar lock will free the heddle bars at their ends so that they will be open and it will be an easy 60 matter to pass heddles which are being removed or being inserted. The heddle bar may be removed if necessary after the lock is released and the operator will have space for his work without interference from the end pieces or any straps or other projections on the end pieces. If the 65 heddle bar be released by opening the lock, as described, the removal of the lower cap screws will permit the entire heddle frame to be removed from the loom leaving the heddles and heddle bars undisturbed in the loom in relation to the warp. By merely substituting end rods of different 70 lengths for those in use, the structure can be

changed to produce a frame of any depth desired.

Having thus described the invention, I claim:

1. A heddle frame comprising upper and lower rails having recesses in their upper and lower edges and having concave end edges, plates secured in the recesses in the rails and projecting beyond the end of the same and provided with eyes at their ends, spacing sleeves fitted between the projecting ends of said plates and against the ends of the rails, end rods disposed between the plates secured to the upper and lower rails and aligned axially with the sleeves, and cap screws inserted through the ends of the plates and the sleeves into the end rods and having threaded engagement with the ends of said rods, the heads of the screws abutting the outer plates whereby the rails and the end rods will be firmly clamped together. 5

2. A heddle frame comprising top and bottom rails, end bars disposed between the ends of the rails, inner plates countersunk in seats formed in the lower edge of the top rail and the upper edge of the bottom rail and having extended end portions abutting the ends of the end bars, outer plates countersunk in seats formed in the upper face of the outer bar and the lower face of the lower bar and having extended end portions, sleeves between the extended end portions of said plate bearing against ends of the upper and lower bars, bolts extending through said sleeves and the extended end portions of said plates and having their inner end portions threaded and screwed into ends of the end bars for clamping the end bars against the extended end portions of the inner plates, heddle bars disposed between the end bars and parallel with the rails, studs anchored in said plates and extending past the ends of the heddle bars to receive and support the same, and locking sleeves mounted on said studs and engaged with the heddle bars to retain them seated in the studs. 20

3. In a heddle frame, top and bottom rails, heddle bars disposed parallel with the rails, studs anchored upon the rails and provided adjacent their free ends with recesses to receive the ends of adjacent heddle bars and support the same and provided between said recesses and the adjacent rails with shallow recesses, and locking sleeves movably mounted on the studs and provided with recesses to admit the heddle bars and with slots 25 extending from said recesses to engage over the heddle bars and retain the same, said sleeves being provided with resilient lips to engage and play in the second-mentioned recesses in the studs and abut the ends of said recesses whereby 30 to normally prevent release of the sleeve from the stud when the sleeve is moved to open position 35 to release the heddle bar. 40

4. In a heddle frame, top and bottom rails, heddle bars arranged parallel with the rails, studs anchored upon the rails and extending past the ends of the heddle bars and provided with recesses adapted to receive and support the heddle bars, and locking sleeves movably mounted upon the studs and provided with recesses to admit the heddle bars and with slots extending from said recesses to engage over and retain the heddle bars, there being a resilient tongue on the sleeve to bear against the side of the heddle bar when 45 the sleeve is in locking position. 50

GEORGE F. BAHAN.
